United States Patent Office.

WILLIAM GLEASON, OF ROCHESTER, NEW YORK.

Letters Patent No. 70,830, dated November 12, 1867.

IMPROVED TOOL-REST.

The Schedule referred to in these Letters Patent and making part of the same.

TO ALL WHOM IT MAY CONCERN:

Be it known that I, WILLIAM GLEASON, of Rochester, in the county of Monroe, and State of New York, have invented a new and useful "Rest for the Tool-Holder of Engine-Lathes;" and I do hereby declare that the following is a full, clear, and exact description thereof, reference being had to the accompanying drawing, making part of this specification, in which the figure is a vertical central section of my invention.

This invention relates to that class of engine-lathes in which it is impracticable to use a weighted tool-rest; and its nature consists in providing a rest for the tool-holder of such lathes, which will permit the tool to be raised or lowered, as may be desired, and without loosening it in the holder.

To enable others to make and use my invention, I will describe its construction and operation.

I make the sliding bed A in the ordinary way, except the addition of a vertical hole in the centre, for the reception of the clamping-swivel V. There is a hole drilled in one side, large enough to receive the eccentric portion C of the clamping-shaft Y, the outer end of which is squared to take the wrench W, the hole being made with a smaller drill beyond the swivel, for the journal-bearing for the inner end of the clamping-shaft. The outer bearing is formed by the bushing b, which is secured in place by the set-screw a. There is a round seat on the upper face of the sliding bed A, to receive the annular rotary gauge G, which is firmly secured to the bed by the annular plate P, and a series of clamping-screws, S. The gauge G is provided inside with one or more turns of a coarse screw-thread or inclined plane, e. Above this thread is a rim, r, made to fit loosely in the groove d of the rest D when it is lowered, and by this means the dust and dirt are prevented from entering the working joints. The rest is threaded to fit the thread in the gauge-ring G. The centre of the rest D is bored out and threaded, as shown, to fit the thread J on the upper end of the clamping-screw S. Both of these threads, e and J, are right-hand threads, but the lower end of the clamping-screw is provided with a left-hand thread, f, corresponding with that in the top of the clamping-swivel or nut V. The lead of the threads J and f should equal that of the thread e. The necessity of this, it will be seen, is owing to the fact that the clamping-screw S is made to turn with the gauge-ring G by means of the lever-pin E, which fits snugly in the ring at g, and through the stem of the screw S, where it is allowed a little vertical play. When the ring G and screw S are given a full turn in the direction to raise the tool-rest D, the screw will be raised as much as the lead of the threads f, consequently that elevation must be compensated for by a corresponding diminution in the lead of the threads J. The parallelism of the rest D with the sliding bed A is maintained by means of the bolt F, which is screwed firmly into the rest, and is nicely fitted into the bed A, as shown. The gauge-ring G can only be turned one revolution less the diameter of the bolt E. The ring may be turned by inserting the end h of the wrench W into one of the holes k, there being several provided in the ring. When the desired elevation or depression of the tool or cutter is obtained, the parts are firmly bound together by turning the cam or eccentric C down. The plug-screw n closes the oil-hole for the inside screw, &c. These tool-rests are attached to the lathes in the ordinary manner, and may be easily applied to those already in use. Any slack or looseness that might occur from wear between the parts, may be compensated for by removing the pin E and giving a half turn or more to the screw S. Instead of the screw f, that end of the screw S may be swivelled to the clamping-nut V by a halved screw-collar. The eccentric clamp C may be dispensed with by substituting a taper pin or key to bind or clamp the parts firmly together when the desired set of the cutting-tool is obtained.

What I claim as my invention, and desire to secure by Letters Patent, is—

1. The employment of the triple-screw system, substantially as herein set forth, for the purpose of adjusting vertically the cutting-tool of engine-lathes without loosening it.
2. The arrangement of the eccentric clamping-shaft Y, in connection with the clamping-screw S and rest D, substantially in the manner hereina shown and described, and for the purposes set forth.

WILLIAM GLEASON.
